4 Claims. (Cl. 250—27)

1

This invention relates to the acceleration of charged particles. It is particularly concerned with a method and means for accelerating charged particles to very great velocities. More specifically the invention relates to achieving the acceleration of ions to speeds approaching that of light by means of a magnetic resonance accelerator; a mechanism of the type known as a cyclotron.

A detailed description of a conventional cyclotron will be found in U. S. Patent No. 1,948,384 granted to E. O. Lawrence on February 20, 1934, entitled "Method and Apparatus for the Acceleration of Ions." The characteristics of cyclotrons of various designs are described in Radiology for November 1942 (vol. 39, No. 5, pages 513-540) under the caption "The Cyclotron: A Nuclear Transformer," by P. C. Aebersold. In this article it is stated that the essentials are a large electromagnet with circular poles, a vacuum chamber, and two electrodes that alternate in potential. The vacuum chamber is positioned between the poles of the electromagnet and contains the two hollow semicircular electrodes usually referred to as Dees which are coplanar radially and whose open diametrical edges are parallel and closely spaced. The particles to be accelerated are usually protons or deuterons formed by stripping the electrons from hydrogen or deuterium atoms. The stripping is accomplished in an ion source at the center of the vacuum chamber and between the Dees and therein the hydrogen or deuterium gas is subjected to electron bombardment. Helium nuclei may also be accelerated in cyclotrons and are obtained by introducing helium gas in the ion source and subjecting it to electron bombardment.

A positive ion introduced between the Dees is pushed by the positive Dee and pulled by the negative one, thus being accelerated across the gap between them. Once the ion is urged into the cavity of a Dee it is no longer influenced by the electric field which has just accelerated it across the gap but is constrained by the magnetic field that is constantly applied, to travel in a circular path. When the particle has progressed along the circular path about 180° it emerges into the region between the Dees where it once more is acted upon by both the magnetic and the electric fields. If the time which the ion has spent within the Dee is just half of the period of oscillation of the high-frequency circuit, then on emergence into the gap, the electric field will be reversed and the particle will once more be accelerated across the gap and into the

2

electrically field-free region within the opposite Dee. The length of path taken within the Dees, between successive accelerations in the gap, increases as the particle progresses. Thus, the particle spirals outwardly because as it gains speed, it has more centrifugal force.

It has been demonstrated that within limits the speed of the particle increases at such a rate that the time of travel between accelerations is constant. Thus, it takes the same time to go around a small semicircle slowly as to go around a large semicircle rapidly. Therefore, the Dees may be energized by plus and minus alternations of constant frequency. This becomes more clear when one considers the motion of an ion mathematically. For a charged particle moving at right angles to a magnetic field one has the relation:

$$20 \quad Hev = \frac{mv^2}{r} \quad (1)$$

where H is the field intensity, e is the charge, v the velocity, and m the mass of the particle and r is the radius of curvature of its path. Now if the ion is allowed to traverse its semicircular path with an angular velocity equal to W then:

$$30 \quad W = \frac{v}{r} \quad (2)$$

and also:

$$35 \quad W = \frac{He}{m} \quad (3)$$

It is evident from this that the angular velocity of the ion is dependent of both its linear velocity and the radius of its path, or more precisely, of the energy of the ion. This is true only for particle velocities that are small compared with the velocity of light. Furthermore it is evident that as the velocity of a particle increases, its energy or mass also increases.

Early in the development of the cyclotron it was recognized that the relativity increase of mass posed an obstacle in achieving very great particle energies therein. H. A. Bethe and M. E. Rose, in a letter published in the December 1937 issue of The Physical Review stated that it was apparent that a cyclotron could not be made to give much higher energies to particles than those which had been obtained at that time. The difficulty is due to the relativistic change of mass which has the effect of destroying either resonance or focusing.

As is frequently the case in experimental physics it is theoretically possible to get around this

apparent practical limitation in several ways. The defocusing action which is inherent in a radially increasing magnetic field required by the relativity condition can be overcome by providing suitable electrostatic focusing. Thomas has shown that an azimuthal adjustment of the magnetic field will accomplish the same purpose. Each of these plans has inherent drawbacks and neither has been successfully reduced to practice.

Again, Bethe has suggested that the only way to obtain higher particle energies in a cyclotron seems to be to increase the voltage on the Dees. Lawrence followed the suggestion when he built his 60" cyclotron in Crocker Laboratory to operate with about a quarter of a million volts on the Dees, to the end that when he was accelerating doubly charged helium ions to 32 million electron volts, the ions were required to circulate fewer than fifty times. The advantage of such a scheme was that a rather large change in mass could take place without seriously impairing the synchronism of the circulating ions. However when it is considered that the particle energy limit increases only as the square root of the Dee voltage, it is easy to see that even such a design as this has limitations beyond which it is not practical.

As previously stated, within limits the speed of a particle revolving in a uniform magnetic field and oscillating electric field increases at such a rate that the time of travel between accelerations is constant. In other words, within limits the particle stays in phase with the oscillator. As the particle velocity approaches that of light, its energy increases and its mass becomes relatively greater. The increase in mass retards the particle and causes it to lag the oscillations of the electric field. It is then out of synchronism with the oscillator and will become increasingly out of phase until it enters a region of deceleration whereupon its energy will drop back to the original value. It is obvious then that there exists a range of phase in which a particle will receive acceleration and beyond which it will not receive acceleration.

Pondering the prospect of completing a cyclotron larger than had ever been built before—not merely were the poles to have been three times the diameter of any previous model but the Dee potential was planned to be 1,000,000 volts and the oscillator power was set at 5000 kw.—I have devised a solution of this problem of phase stability as it applies to magnetic resonance accelerators. The term "phase stability" as here used refers to particles kept in phase with the oscillating electric field even after great mass increases have taken place therein. If one were to increase the magnetic field incrementally, or to decrease the electric frequency incrementally, the equilibrium angular velocity of the affected particles would then be sufficiently in excess of the value required to match their gain in energy that the instantaneous value of the energy of the particle would oscillate back and forth about the equilibrium value. Thus the energy of the charged particles traveling in substantially circular orbits in a magnetic resonance accelerator would be phase stabilized about the equilibrium value.

The utilization of the principle of phase stability for accelerating charged particles to high energy may be achieved in different ways for light and heavy particles. For the acceleration of light particles, such as electrons, to high energy it is more convenient to vary the magnetic field and

hold the frequency of the electric field constant, and this technique has been used in the synchrotron which is disclosed in the copending application of Edwin M. McMillan, Serial No. 666,908, for "Method Of And Apparatus For Accelerating To High Energy Electrically Charged Particles." For the acceleration of heavy particles, such as protons, reuterons and alpha particles, to high energy, it is more convenient to hold the magnetic field constant and vary the frequency of the oscillating electric field. This technique is employed in the instant improvement in a cyclotron to meet the requirements of fundamental researchers for an instrument which will supply charged particles at very much higher energy than has been obtainable heretofore.

It is therefore one object of this invention to provide a method and means for accelerating charged particles to energies commensurate with substantial increases in the mass of the particles.

Another object of the invention is to provide a method and means employing an oscillating electric field and a magnetic field for controlling the energy of charged particles by varying the ratio of the frequency of oscillation to the magnetic field strength.

Another object of the invention is to provide a method and means employing an oscillating electric field and a magnetic field for increasing the energy of charged particles by decreasing the frequency of oscillation of the electric field.

A further object of the invention is to provide a method and means employing a magnetic field and a varying oscillating electric field for accelerating charged particles along circular orbits in a cylindrical region and for directing the particles to a target in the outer portion of that region.

Other objects and advantages of the invention will become evident with reference to the following detailed description in conjunction with the accompanying drawings wherein:

Figure 1 is a diagrammatic plan, comparable to a cross section on a generally horizontal plane taken between the poles of the magnet.

Fig. 2 is a front elevation of a magnet structure and a form of the invention associated therewith but illustrating primarily the envelope or tank of the embodiment with portions of various tank appurtenances omitted.

Fig. 3 is a view of the structure shown in Fig. 2, being generally a plan with portions of the magnet and tank broken away to increase the clarity of disclosure.

Fig. 4 is a view of the structure disclosed in Fig. 3, the view being in part an elevation and the remainder a vertical cross section, and the several planes of the whole being indicated by the line 4—4 of Fig. 3.

Fig. 5 is an end elevation partly in section on the line 5—5 of Fig. 4 showing to an enlarged scale the rotary condenser and its associated structures, with portions broken away to reduce the size of the figure and to improve the clarity of disclosure.

Fig. 6 is a cross section on a vertical plane indicated by the line 6—6 of Fig. 5, showing mechanical details of the rotary condenser with fragments broken away to increase the clarity of disclosure.

Fig. 7 is a fragmentary view of portions of the rotary capacitor shaft showing, in section, details of the water cooling means.

Referring now to Fig. 1 there is illustrated schematically an electromagnetic accelerator embodying the present invention and which I have

termed a synchro-cyclotron. The synchro-cyclotron 11 comprises a magnetic field structure of which one pole 12 is shown, a tank 13 arranged on a common vertical axis therewith, and a pair of electrodes 14 and 15 for establishing the required electric field. The electrode 14 as shown is a hollow, generally semipancake-shaped member with its diametrical edge open and facing electrode 15 but with its curved edge substantially closed. Electrode 15 consists of a pair of metal skinlike coverings overlaying and suitably secured to the respective poles of the magnetic field structure, one of the coverings forming the electrode 15 being shown affixed to the pole 12. The two portions of electrode 15 are formed on their diametral edges into lips which are spaced apart a distance equal to the distance between the side-walls of electrode 14. The electrodes 14 and 15 are enclosed within the vacuum tight envelope or tank 13.

The electrode 14 is insulated from the tank 13 being supported by stems 16 and 17 that are secured to the wall 18 of electrode 14, and pass through insulators 19 and 21 which in turn are supported on a wall of the tank 13. The electrode 15 is electrically grounded through the pole 12, and since the poles may either support the tank 13 or be part of the tank, the electrode 15 is also electrically grounded through the tank 13.

Through a port 22 and a manifold 23, two diffusion pumps 24 backed up by a motor driven pump 25 are used to maintain the necessary vacuum within the tank 13.

A high frequency oscillatory electric field is maintained between electrodes 14 and 15 by applying to electrode 14 a high frequency oscillating potential supplied from an electronic oscillator, the grounded electrode 15 being connected through the tank to one side of the oscillator. The oscillator circuit may be of any suitable type, such as the grounded grid circuit shown in Fig. 1, comprising an oscillator tube 26 and suitable inductances and capacitances to produce an oscillator having a definite frequency. The input of the oscillator is connected to a power supply which is fed from a 60 cycle line 27. The plate potential of about 15 kv. is fed in at the junction point 28. Grid bias is developed across the dropping resistor 29 and the radio frequency on the grid is by-passed to ground through capacitor 31. The phase of the excitation voltage between filament and grid is controlled by the capacitor 32 in series with the filament lines.

As a means of exciting the electrode 14 from the output of the oscillator, the filament lines are connected to a filament coupling loop 33, and the plate line is connected to a plate coupling loop 34. These loops 33 and 34 are arranged in parallel relationship adjacent the electrode stem 16 (Fig. 1) which constitutes a half-wave transmission line. It would of course be possible to use any convenient number of these transmission lines in parallel but for simplicity of illustration only two are shown in Fig. 1. The filament and plate loops may be arranged adjacent any one or two of the transmission lines.

The ends of the stems 16 and 17, opposite the electrode 14, are supported by insulators 35 and 36 respectively and terminate in a rotary capacitor 37 enclosed in a vacuum tight tank 38. Secured to the stems are a number of spaced, fixed rings 39 with toothlike blades projecting inwardly therefrom. Interposed between the fixed rings are rotatable disks 41 mounted on an insulator 42 which in turn is secured to a shaft 43 that

is driven by an external motor 44 through a pulley 45. The disks 41 are also provided with peripheral blades, and their extent and spacing are substantially identical with those on the fixed ring 39. A second series of capacitor plates is located in the tank 38 and constitutes a coupling capacitor to ground. It comprises a rotating disk 46 mounted on the insulator 42 and positioned midway between two fixed rings 47 mounted on a wall of tank 38.

A positive bias of a few hundred volts is applied to the electrode 14 and the stator rings 39 through the choke 48 and the electrode stem 17. The radio-frequency potential on the electrode stem 17 is by-passed to ground through the capacitor 49.

Ions may be provided in the apparatus by any suitable means. Fig. 1 illustrates an ion source 51 positioned over the center of the pole 12 and supported at the end of an arm 52 midway between the electrodes 14 and 15. The arm 52 is sustained by an insulator 53 in the wall of the tank 13. The filament in the ion source 51 is energized through conductors 54 and a transformer 55 by a 60 cycle alternating current. Direct current is provided to the source 51 through a junction 56 by a pulsed supply 57 which can provide up to one thousand volts.

Means are provided for sampling the ion current in any of the circulator orbits of the beam which are in a generally horizontal plane midway between the magnet poles. The supporting tube 58 is slidably arranged in a wall of the tank 13. As is common in cyclotron art the tube 58 is provided with an aperture 59 to receive the beam. Therein the beam falls on an electrode that is insulated from the shell of the tube and current flows along an insulated conductor 61 through the current meter 62 to ground. The tube 58 may be moved axially through the several beam revolutions and therefore it may be positioned to intercept any single revolution of the beam from a point adjacent the source to the outermost revolution. Thus one may measure the ion current in the beam at any point along a radius of its circulatory orbits.

At a definite point in the circulator path of the beam means are provided for withdrawing the ions from the magnetic field. For this purpose there are shown, for example, electrodes 63 and 64 which delimit an electric field designed to receive ions and deflect them outwardly. The electrode 63 is a curved metal structure mounted within and electrically grounded to the tank 13, and extending from a point of tangency to the path of the ions in the magnetic field but flared outwardly therefrom. Concentric with electrode 63 is an electrode 64 comprising a curved metal strap that is mounted on a pair of supporting members 65 and 66. The supports 65 and 66 are in turn respectively mounted on insulators 67 and 68 which are formed as bushings, secured to a wall of the tank 13. An adjustable external source of direct current supplies a suitable potential on the order of 200 kv., as an example, to the electrode 64 through the conductors 69 which pass through bushings 67 and 68, and are connected to the respective supports 65 and 66. When positively charged particles are being operated upon, the electrode 64 is maintained at a suitable negative potential to withdraw the particles from the magnetic field. The grounded electrode 63 serves to prevent the field set up around the electrode 64 from having

any effect on the orbits of the beam. Thus the electrodes 63 and 64 constitute a deflector system which is capable of deflecting the charged particles in the outermost revolution of the beam orbit outwardly from the region of the magnetic field.

The particles thus affected pass through the channel 71, between the electrodes 63 and 64, and emerge from the outlet opening 72 into a region of diminished magnetic field wherein their centrifugal force causes them to traverse an ever straightening path 73 into the electrode 14 and through a window in the wall 74 thereof.

The high speed particles emerging from the Dee along the path 73 may be utilized in any suitable manner such as operations upon atomic structures, in medical physics research, etc. To facilitate such investigations the high speed particles may be withdrawn from the apparatus through a window 75 provided in a wall of the tank 13. The window may be made of any suitable material which will at once maintain the vacuum tight continuity of the tank structure and yet permit the passage of the emergent particles therethrough without appreciable velocity loss or scattering.

Cyclotrons have been widely discussed in the literature. As an example, a comprehensive paper dealing with the prior art in such matters as magnet design, ion sources, deflectors, target arrangements, vacuum systems and shielding appeared in the Journal of Applied Physics in January 1944 (vol. 15, pages 2-19) and in February 1944 (vol. 15, pages 128-247) under the title "The Cyclotron," by M. S. Livingstone. Whereas the above disclosure is adequate as a general catalogue and identification of the apparatus composing the complete synchro-cyclotron, the following description of the present embodiment of the invention will aid in understanding its construction, operation and worth.

In the giant synchro-cyclotron as constructed (Figs. 2 and 3), the electromagnet includes an upper pole 81 having a generally horizontal, circular pole face 82 spaced in parallel relationship from a lower pole face 83 of a lower pole 84. The surface of the upper pole face 82 while substantially planar is provided with steps 85 arranged in the form of rings near the periphery of the upper pole 81 (Fig. 4). The surface of the lower pole face 83 is similar in area and configuration to the upper pole face, being provided with steps 86. Magnetic flux between the pole faces is maintained by energized electric coil windings 87 and 88 girdling the poles 81 and 84 respectively and disposed within the encompassing yoke or frame 89 which constitutes a dual return path for the magnetic flux. In operation the coil windings are effective in maintaining a substantially homogeneous and non-varying magnetic field, the flux direction of which is perpendicular from the lower pole face 83 to the upper pole face 82. The steps 85 and 86 in the respective pole faces reduce the gap therebetween near their edges and are effective in maintaining a uniform magnetic field adjacent the marginal edges of the poles—a region wherein a magnetic field maintained between poles lacking these characteristic contours would be distorted.

A vacuum envelope or tank 91 is positioned around and secured in vacuum tight relationship to the poles 81 and 84. The tank 91 of the giant synchrocyclotron is about twenty feet square as viewed from above (Fig. 3) and is so oriented that

one of its diagonals approximately coincides with the center line of the magnet frame 89. The upper wall 92 of the tank 91 is provided with an aperture 93 of sufficient size to fit around the upper pole 81 and permit the wall to be secured to a flange 94 formed around the pole 81, with a plurality of gaskets (not shown), clamping lugs 95, studs 96 and nuts 97. Similarly the lower wall 98 of the tank 91 is provided with an aperture 99 sized to encompass the lower pole 84 and permit the wall to be secured to a flange 101 formed around the pole 84, with a plurality of gaskets (not shown), clamping lugs 102, studs 103 and nuts 104.

In addition to the support given the tank 91 by the clamping systems on the magnet poles 81 and 84, it is also held in place by a set of four stanchions 105; one under each of its corners (Fig. 3).

The opposing vertical walls 106 and 107 in the tank 91 are each provided with a number of flanged ports and a third vertical wall is comprised of a cover plate 108 secured by bolts 109 and nuts 111 to a flange 112 with deformable gasket material interposed between the flange and the plate to effect a vacuum seal. The fourth vertical sidewall of tank 91 is similarly closed with a face plate 113 secured by bolts 114 and nuts 115 to a flange 116, and with gaskets interposed between the flange and face plate to form a vacuum seal.

Secured to the flanged port 117 in the side wall 108 is a manifold 118 for junction with a pair of diffusion pumps 119 and 121. The diffusion pumps may be used in combination with a mechanical vacuum pump as shown diagrammatically in Fig. 1 to provide vacua on the order of 10^{-5} mm. Hg in the tank 91.

The ion source 122 for the synchro-cyclotron is essentially the same as those used in the early model cyclotrons to which reference has been made. It comprises a tubular arm 123 supporting at its inner extremity 124, in the region between the centers of the pole faces 82 and 83, means for maintaining an arc, and supported at its outer end by a face plate 125 secured to the flanged port 126 in the wall 106 of the tank 91. The arc may be maintained by any suitable means such as a filament and an anode. A gas such as hydrogen is introduced into the region between the filament and the anode through the supporting arm 123 and the arm also carries electric conductors to supply current from an exterior source of D. C. to the filament and anode. The face plate 125 also carries adjusting means 127 for orienting the extremity 124 of the arm 123 to the end that the ions produced will be made available at the center of the magnetic field.

The ion source appurtenances mounted on the face plate 125 also include means 128 for the introduction and regulation of the gas to be ionized and for introducing the electric conductors to the tubular arm 123.

As I have stated above in connection with the diagrammatic view in Fig. 1 the present invention employs but a single Dee, the other being replaced with a grounded electrode. The Dee 129, so-called because of the shape of a prototype, is supported by the face plate 113 on a bulge 131 formed therein. Bulge 131 extends through the mid-portion of the plate 113, transversely, and consists of two flat plates, the upper plate 132 forming an angle of about 30° with the main plate 113 and the lower plate 133 being parallel

to the major portion of plate 113. The bulge 131 is enclosed on the lower side and on the ends to make possible the maintenance of vacua within the tank 92.

The Dee 129 which in the giant synchro-cyclotron weighs on the order of a ton is carried by four hollow cylindrical ceramic insulators, two of which 134 and 135 are shown in Fig. 4. It will be understood from Fig. 4 that the two upper insulators are mounted on the plate 132 and the two lower insulators are similarly mounted on the plate 133. All four insulators are concentric with apertures in the bulge 131 and are secured in a vacuum tight manner to the latter by means of clamping rings 136. Other clamping rings 136 form vacuum tight seals against capping disks 137 at the outer ends of insulators 134 and 135. The disks 137 are provided with re-entrant supports 138 which extend through said hollow insulators and terminate in seats upon which the frame 139 of the Dee 129 is fastened.

The Dee 129 has the appearance of a short wide semicylinder supported on its curved side by insulators 134 and 135. The frame 139 is arranged with curved channels 141, on the sides of the cylinder, supporting a number of small beams 142 and supported by a flared truss structure (shown in vertical section, Fig. 4) which is seated on the re-entrant supports 138. Thus the weight of the Dee is distributed in such a way that the two upper insulators are in tension and the two lower insulators are in compression. The frame 139 is fabricated of aluminum alloy to reduce its weight to a minimum and is substantially enclosed with a thin copper skin 143 to define the electric field. On the open diametral edge of the Dee the copper skin is formed into an upper lip 144 and a lower lip 145. These lips extend beyond the line between the ends of the channels 131 and nearly to the center line of the poles of the magnet. The frame 139 also supports the weight of a labyrinth of copper tubing (not shown) hard soldered to the inside of the Dee skin 143 to carry cooling water to all parts of the Dee as is common in the art. This serves to prevent the operating temperature of such an electrode from becoming excessive.

The grounded electrode 146 is made up of a pair of thin copper skins, one mounted on a section of the upper pole face 82 and formed to fit over an arc of the steps 85 and the other mounted on a section of the lower pole face 83 and likewise formed to fit over the steps 86. The electrode 146 is similar in area and shape to the Dee 129 and is flared at the support end of the frame 139 to encompass the latter in a spaced relationship. The inside surface of the bulge 131 is also covered with a copper lining 147 designed to meet the pair of skinlike sheets comprising the electrode 146 when the face plate 113 is secured to the flange 110. The lining 147 is provided with apertures to admit the protruding re-entrant supports 138. The apertures are much larger in diameter than the supports 138 thus insuring against the grounding of these parts. On their diametral edges the two major constituents of electrode 146 are fashioned into lips 148 spaced apart vertically a distance equal to that between the lips 144 and 145 of the Dee 129. This vertical clearance between parts of the electrodes 129 and 146 in the giant cyclotron described is approximately five inches and it has been found that this is ample to accommodate the oscillations of the charged particles about the median plane. In Fig. 3 I have shown how the lips of the electrodes

129 and 146 are similarly contoured horizontally so that the interval therebetween is uniform throughout.

The insulators that are mounted on the face plate 113 and referred to hereinbefore, serve as connecting links between the Dee and an oscillator (Fig. 1).

The oscillator together with its associated equipment is preferably carried on a portable truck structure that may be rolled into place for operation or out of place for service on a pair of rails 149 imbedded in the floor of the synchro-cyclotron building. The truck 151 consists of a lower main frame 152 made of structural steel and mounting a number of flanged wheels 153 engaging the rails 149, and an upper framework 154 adjustably anchored to the frame 152 by means of a plurality of brackets 155 and screw-jacks 156. The truck 151 may be impelled in either direction by an electric motor 157 driving one of the wheels 153 through a gear train 158 and a chain belt 160. At the end of the framework 154 that is adjacent the tank 91 a pair of braced, vertical arms 159 are provided to be attached to, and bear the weight of, the face plate 113. The framework 154 includes two sets of rails 161 and 161a mounted on cross-members and each carrying a smaller truck. The rails 161 carry truck 162 on a set of unflanged wheels 163 and a set of flanged wheels 164 while the rails 161a carry truck 162a on a set of unflanged wheels 163a and a set of flanged wheels 164a. At that end of the truck 162a which is adjacent the face plate 113 of the tank 91 there are a pair of rails 165 placed transversely thereon and provided to support another truck 166 through engagement with the interposed wheels 167. Although the frame 166 is little more than a small rigid frame it is sufficiently sturdy to transport the weight of an oscillator house 168.

The shield 169 is supported on truck 162a and encloses a set of four transmission lines, two of which (Fig. 4) are coupled to the supporting insulators for the Dee. The large copper tube 171 which constitutes one of such lines is secured to the capping disk 137 on the insulator 135. The other one of the lower pair of lines is identically constructed, and is mounted on the second one of the lower pair of insulators. The large copper tube 172 is also identified as one of the lines which is secured to a capping disk 137 on the insulator 134 through the medium of a transition member 173. Here again the other one of the upper pair of lines is identical. Shield 169 which encloses these four parallel transmission lines is a thin walled metal shell stretched on small section channel ribs. It is preferably fabricated in sections for ease in assembly or disassembly. One of the walls of the shield 169 is common to the oscillator house 168 which is similar in construction thereto, and which houses the oscillator tube and its associated circuit components. It will be apparent that the complete shielding of the oscillator system herein provided insures a minimum of radiation therefrom.

The oscillator and its appurtenances dissipate a considerable amount of heat which it is desirable to remove from the confines of the oscillator house. To accomplish this I have mounted a pair of small, motor driven blowers 174 and 175 on the top of the oscillator house 168. These blowers do not cool the oscillator per se, since it is a water cooled triode, but serve to draw in filtered air and blow it down over the filament leads of the triode and also over the coupling loops in the

filament and plate lines. The cooling air leaves the oscillator house through screened windows in the walls thereof.

The four transmission lines comprising the tubes 171, 172 and their paired complements, together with the shield 169 are constituents of a resonant system whose effective length is that of one half wave. The system is so arranged that a voltage minimum exists near the insulators that support the Dee and voltage maxima exist at the gap between the lips of the Dee and of the grounded electrode, and inside the rotary capacitor. Four lines were used in this design both because of the great weight of the Dee and because the large electrical capacity of the system required either multiple lines or a single line of such low impedance as to be impracticable.

The coupling of the oscillator to the transmission lines is accomplished in a manner similar to that shown schematically in Fig. 1. The large tube 172 is split for a distance along the side and the edges of the split are rolled away from each other to form lips. The opening thus formed is large enough to admit a loop 170 (Fig. 4) in the oscillator cathode line. Similarly the tube 171 is formed to admit a loop (not shown) in the oscillator plate line.

It was calculated that the mass increase of the accelerated particles at high velocities would require an 11% reduction in the applied frequency from the oscillator. A further frequency adjustment was necessitated by the fact that the magnetic field was allowed to decrease radially by 4% to improve focusing. Thus a frequency shift of the order of 15% is necessary theoretically. To accomplish this there is positioned at the ends of the transmission lines opposite the Dee, and affixed on the truck 162, a rotary capacitor 176.

The moving parts of the rotary capacitor 176 are housed in a greatly reduced atmosphere. For such purpose there is provided a tank 177 to contain the environment of vacuum, and the system, of which the tank is a part, is separate and distinct from that provided for the main tank 91. The capacitor tank 177 is welded to a cradle 178 that is bolted to cross-members on the truck 162. A manifold 179 on the tank 177 communicates with the large diffusion pump 181. A manifold 182 intercommunicates between the pump 181 and a small diffusion pump 183. The exhaust passage on the small diffusion pump 183 in turn is connected to the intake manifold 184 of a mechanical vacuum pump 185 that is driven by an electric motor through the enclosed pulley 186. The three pumps and the necessary plumbing and wiring are all carried on the truck 162 along with the rotary capacitor 176.

Considering the tank 177 in detail, the circular cylindrical wall 187 is welded to a rear flange 188 and a forward flange 189. A plurality of tubes 191 are welded between the flanges at uniform intervals coaxially with holes therein and serve as sleeves through which long bolts 192 are passed to engage the cover plates of the tank. The bolts engage the rear cover plates 193 in threaded holes and they pass through the forward cover plate in clearance holes. Interspersed between the long bolts in the plate 194 are a number of short bolts 195 to hold this plate to the forward flange. Thus it is possible by removing the long bolts 192 and leaving the short bolts 195 undisturbed to break the tank 177 at the joint 196 for servicing operations.

The rear cover 193 is weakened by five aper-

tures and to prevent it from sagging inwardly when the tank 177 is under vacuum, crossed stiffeners 197 are welded to its outer surface in the general shape of a plus sign. In section the stiffeners are T-shaped with a web 198 and a flange 199. In the region where the stiffeners cross they are interrupted by and welded to a sleeve 201.

The four transmission lines are supported at 10 their ends opposite the Dee on four insulators 202 that are secured to the plate 193 of the tank 177. Inasmuch as the mountings at their end of the transmission lines are all similar a description of one will suffice for all.

Referring then to Fig. 6, the tube 171 is hard soldered to one side of a mounting flange 203. An insulator 202 is seated in a recess milled in the opposing surface, with a gasket in the seat to prevent damage under pressure. The insulator is of thin walled ceramic construction and is formed with a small lip 204 at each end. Adjacent to and coaxial with the flange 203 is a mounting collar 205 fabricated as a metal annulus peripherally pierced to receive a plurality of machine screws anchored in the flange 203. The annular collar 205 is stepped on its inner face to cooperate with a split ring 206 in bringing pressure to bear on a clamp ring 207 which in turn bears on and distorts the gasket 208 against the lip 204, the flange 203, and the mounting collar 205 to form a vacuum-tight joint. A plurality of screws hold the mounting collar 205 and the split ring 206 together once they have been assembled around the insulator, 35 and a soft copper ring is interposed between the split ring 206 and the lip 204 to safely urge the insulator against the flange.

The other end of the insulator 202 is similarly fastened with an annular collar 209, a split ring 40 211, a clamping ring 212, and a gasket 213; all cooperating to form a gas tight seal when constrained by the plurality of machine screws in the collar 209 toward the insulator lip 204 and the plate 214. A soft copper ring is seated between the split ring 211 and the insulator lip 204 to transmit pressure safely from the former to the latter. The plate 214 is recessed to receive a gasket upon which the end of the insulator 202 bears. Thus damage to the insulator in the clamping process is avoided.

The plate 214 possesses an aperture 215 that is concentric with the insulator and is mounted in a fixed position concentrically over an aperture 216 of greater diameter in the cover plate 193 on the tank 177. A copper sleeve 217 with a copper flange 218 hard soldered around it somewhat nearer one extremity than the other is secured to the inner surface of the plate 214 and inside of the aperture 216 with a number of fasteners through the flange 218. A groove 219 in the periphery of the plate 214, covered with a band 221 serves as a means of circulating cooling water around this plate. The end wall 222 of the shield 169 is affixed to the outside surface of the cover plate 193.

Each of the transmission lines is provided with an electric current carrying structure that is connected to it at the point where it is supported on the insulator 202 and that extends through its insulator and sleeve 217 well into the tank 177. Each of these structures includes a disk 223 positioned inside and concentric with the insulator 202 and held to the flange 203 with several machine screws 224. The extension portion of each structure is a pair of tubes 225 and 226 coaxial

with each other and with the surrounding insulator 202 and sleeve 217. These tubes are hard soldered to the disk 223 for support, and at the opposite ends they are individually sealed.

A uniform space between the tubes is maintained by a helix 227 which forms a helical passage for cooling water. The water is introduced by suitable means through a tube 228 and after flowing through the passage leaves via a hole in the disk 223, a fitting 229, and a tube 231 to circulate through the Dee 129. Although not deemed necessary to specifically illustrate, it will be understood that the water then leaves the Dee through a tube 232 that passes through the seals at the ends of the tubes 225 and 226.

The circulation of cooling water inside the insulators is necessitated by the voltage maximum that exists in the system near this region. This high voltage causes heating in the insulators, and the heat must be removed to prevent their ultimate failure. As a further means of removing heat from the insulators, air ducts convey cool air to them.

As shown in Fig. 5, a suitable bracket 197 mounting the vertical stiffener 197 bears an electric motor 233 that drives a blower 234. The latter draws in filtered air and forces it through the four ducts 235. Each duct conveys air to a single insulator through an opening in the sectional transmission line shield 169. Thus, the interiors of the insulators, which share the vacuum that is maintained in the rotary capacitor tank, are water cooled and the exteriors of the insulators are air cooled.

The four extensions of the transmission lines provide support for the static members of the rotary capacitor (Fig. 6). The outer tube 225 of each of the upper two supports is notched to receive either end of a bar 236 which is secured therein. Midway the bar is drilled to receive a stud 237. Each of the lower two supports mounts a stud 238 fixed in the center of its end. The studs 237 and 238 with the aid of stop nuts as shown hold a thick metal plate 239 at three points in an adjustable vertical position. A heavy ring 241 welded to the plate 239 serves to make it rigid.

The upper corners of the plate 239 are trimmed off immediately outside the ring 241, and a large circular portion of its center has also been cut out. Whereas the bar 236 and the stud 237 are adequate as an adjustable support for the plate 239, they do not provide an adequate electrical path for R. F. currents that appear on the extensions. Therefore a thin copper section 242, shaped somewhat like the plate 239 and secured to its back surface, is provided with ears formed to overlay the ends of the upper extensions; the ears are held thereto by rings 243 and fasteners 244 and thereby provide supplementary paths for the current. The lower corners of the section 242 are similarly formed and are clamped against the ends of the lower extensions with rings 243 and fasteners 244.

The plate 239 is provided with a plurality of holes whose centers are equidistant on a circle of somewhat lesser radius than that of the ring 241. A series of metal fingers or blades 245 are held in uniform alignment on a bolt 246 in each of the holes in the circle on the plate 239. A spacing washer 247 is mounted between each of the blades on each bolt; in a blade, washer, blade sequence, with a washer and a nut 248 on top of each assembly. The blades each taper to a re-

duced dimension toward their tips which point toward a common center.

The rotating members in this capacitor comprise a series of spiders 249 each formed as an annulus with radiating coplanar blades 251 projecting from its periphery at uniform intervals. The blades on each spider are the same in number as are the bolts 246 that hold the blades 245 of the stator, and the number of spiders is one less than the number of blades on each bolt 246. The annular portions of the spiders together with interposed rings 252 are held rigidly secured to a hub 253 with a number of bolts 254.

The hub 253 is seated on a pair of heavy supporting annuli 255 and 256 that in turn are borne by and keyed to an elaborate arbor or shaft 257. The supporting annuli are made of a material, for example a ceramic, that has good electrical insulating characteristics and high mechanical strength. The annulus 255 is locked in a seat in the hub 253 with a clamping ring 258 and a plurality of screws 259 that engage the hub. In a similar manner the annulus 256 is locked in a seat in the hub 253 with a pressure ring 261 that is urged against it by several set screws 262 through a threaded ring 263. The screws 262 are retained by jam nuts 264. External threads in the ring 263 engage internal threads in the hub 253. Gaskets are interposed between the annulus 256 and the ring 261 and also between the annulus 255 and the ring 258 to effect water tight joints.

The shaft 257 passes through a housing 265 that is welded to a flange 266. The housing 265 intrudes the tank 177 through an aperture 267 in the center of the cover 194. The flange 266 is secured to a collar 268 that is held to the cover 194 with a number of studs and nuts. Gaskets between the flange 266 and the collar 268, and more gaskets between the latter and the cover 194 are effective in maintaining vacuum tight joints.

The flange 266 is integral with a casting 269. Bearings 271, 272, and 273 set in the casting support and align the shaft 257 at this end. A short sleeve 274 brazed in the casting 269 contains a conventional chevron seal that when urged against the shaft 257 by a gland 275 forms a vacuum seal. The chevron seal is bathed in oil supplied from the sight glasses 276.

A family of pulleys 277 on the shaft 257 is positioned to receive a belt 278 driven by an electric motor 279 and mounted on a bracket 281 that is bolted on the cover plate 194.

The shaft 257 is hollow at this end from the region near the annulus 256 substantially to the bearing 273. This tubular portion of the shaft may be provided with any desired means of supplying cooling water to the rotating parts of the rotary capacitor 176; for example, a squirt tube 282 (Fig. 7), and said tubular portion originates in that section of the shaft that is within a hollow protuberance 283 in the casting 269. A water fitting 284 in the wall of the protuberance supplies cooling water to an annular chamber 285 therein, and the latter communicates with the input orifice of the squirt tube 282 through small radial bores 286. Water flows the length of the tube 282 and emerges through radial passages 287 drilled in the shaft 257, into the space enclosed by the annuli 255 and 256, and the hub 253.

The volume so defined is divided by a water circulating baffle 288 made of a ceramic material and formed as a flat wheel with a wide flange. The web of this ceramic wheel is held against a

shoulder 289 on the shaft 257 by a pressure ring 291 whose inner surface threadably engages the shaft 257.

After water emerges from the inner tube through the radial passages 287 it is constrained to flow over the surface of the baffle flange where it is in intimate contact with the inner surface of the hub 253, after which it passes through the toroidal chamber 282 and re-enters the shaft 257 via a second set of radial passages 293. An outer water passage 294, defined by the outer surface of the squirt tube 282 and the inner surface of the shaft 257, terminates in the region between the two sets of radial passages where the tube and shaft are sealed together. Thus water must flow outwardly over the inner tube to a point where it is once more within the protuberance 283 and where this passage again terminates. The water leaves the passage here via more radial bores 295, a companion annular chamber 296, and a second water fitting 297. The two annular chambers are separated by a common end wall 298 and share the fixed shell of the protuberance 283 for their outer walls and the rotatable shaft 257 for their inner walls. The opposite end walls are formed by packing glands 299.

The hub 253 is amply proportioned to carry the rotating members of a coupling section designed to by-pass the voltage on the rotating parts to ground. On a portion of the hub with a reduced diameter, a number of annular plates 300 are mounted alternately with spacer rings 301. The assembly is held firmly against a shouldered portion of the hub by a plurality of fasteners 302. Interleaved with the plates 300 are the fixed plates 303 which for ease of assembly are semi-annular in shape. These latter plates are positioned so that each pair forms a complete annular disk. This arrangement provides alternate fixed and movable plates for the coupling section of the capacitor with a fixed member at each end of the assembly. The fixed plates are precisely spaced by spacing rings 304 in such a way that each rotating plate is stationed midway between two fixed plates. The assembly of plates 303 and rings 304 is secured to a heavy flanged ring 305 by a number of bolts 306 and nuts 307.

A plurality of standoff studs 308 and stop nuts 309 provide support for the ring 305 and its load, and the adjustability of the support makes it possible to accurately space the rotor and stator plates of the coupling section of the variable capacitor. The standoff studs are based in the cover 193 of the tank 177.

Although the studs 308 are adequate as supports for the ring 305 they do not provide adequate paths for the currents that this coupling structure is required to carry. For this purpose there is added a thin copper cylinder 311 that is held in contact with the ring 305 by a band 312 and a plurality of screws 313. The cylinder 311 extends to the inside of the tank cover 193 where it is contiguous with a disk-like portion 314 and forms part of the ground path for the current. A good electrical contact with the cover 193 is assured by a ruggedly proportioned ring 315 and a great number of studs 316 and acorn nuts 317. The cylinder is rendered somewhat flexible by a deeply spun, outwardly projecting, annular wrinkle 318 midway on its side, thereby facilitating the adjustment of the position of the ring 305 on the standoff studs 308.

The other end of the shaft 257 is cradled in a set of bearings 319 positioned within an inner sleeve 321 that in turn is enclosed by the coaxial

outer sleeve 322. The latter ends in, and is supported by a flange 323 that is fastened to the cover plate 193 with studs 324 and nuts 325. The inner sleeve may be adjusted axially in either direction within the fixed outer sleeve with the aid of a plurality of adjusting screws 326 and their cooperating jam nuts 327. The screws 326 threadably engage the sleeve 322, piercing the opposing beveled sides of a pair of shoulders 328 and 329. The tips of the screws 326 bear against surfaces provided for the purpose on the inner nonrotating sleeve 321. Axial adjustment of the arbor or shaft 257 may be accomplished by loosening the screws 326 in the beveled surface of shoulder 328 and then tightening the screws 326 in the beveled shoulder 329. Adjustment in the opposite direction may be accomplished by loosening the screws in shoulder 329 and tightening those in shoulder 328. By making the appropriate adjustment of these screws in the sleeve 322, the shaft 257, and hence the hub 253 and the rotating plates carried thereon, may be translated so that the blades 251 can rotate in paths that are equidistant from consecutive fingers 245 on any bolt 246.

To enhance the flexibility of the rotary capacitor the shaft 257 has been extended through the plate 193 well into the sleeve 201 where it terminates in a section of reduced diameter on which is milled a flat 331. This is intended as a seat for a possible future addition. Surrounding the end of the shaft is a tube 332 with a ring 333 welded to it at one end and a disk 334 welded to it at the other end. Between the ring 333 and the plate 193 are two rubber gaskets. A plurality of bolts 335 urge the disk, tube and ring toward the plate 193 thus squeezing the gaskets to form a vacuum tight joint.

A viewing port 336 is situated on the front cover plate 194 of the rotary capacitor 176. The flanged pipe 337, welded around the aperture 338, serves as a base for a thick glass window 339. A clamp ring 341 drawn toward the flange by a number of fasteners 342 deresses gaskets on either surface of the window and seals the vacuum in the tank 177.

Motor 279 for driving the shaft 257 is remotely controlled by a suitable speed varying device, preferably of the electronic type. The hub 253, upon which the rotating parts of the capacitor are mounted, is carried on the arbor by the insulating disks 255 and 256. The latter are preferably made of zircon porcelain. Disks 255 and 256 serve to prevent the R. F. currents from flowing in the arbor bearings eliminating the necessity of sliding contacts.

The signal that is induced in the transmission lines by the filament and plate coupling loops of the oscillator flows through the tubes 225 inside the insulators 202, through the thin copper section 242, to the plate 239, and the stator fingers 245.

The blades 251 on the spiders 249 modulate the R. F. signal from the oscillator as they rotate between the stator fingers 245. The degree or percentage of modulation is a function of the speed of rotation of the spiders 249. The R. F. signal is by-passed to ground through the coupling section of the capacitor. The rotatable plates 300 and the stationary plates 303 that form the coupling section are sufficient in number and area to provide a capacitance of the order of ten times the maximum capacitance of all the blades in the modulating section.

All of the inner surfaces of the tank 177 are

heavily copper plated to provide a better path for the R. F. currents than the steel tank alone could provide. This serves to reduce heating effects and minimize the need for cooling mediums. For like reasons, all of the major parts in the rotary capacitor, that are not made of copper because of strength requirements, are also heavily copper plated.

The flange-like copper disk 314 has four circular areas cut out to receive the four sleeves 217 with a snug fit. The joints are preferably hard soldered. Each sleeve 217 is made to extend well into its insulator in order to protect the insulator from the field that otherwise would exist between the tube 225 and the split ring 211 in the clamping mechanism. In that case the field would induce heating in the insulator, and because of the unequal wall thickness at the flange 204 the heat would cause it to fail after brief operation.

Thus the return path for R. F. current includes the sleeves 217 and their mounting flanges 218, the plates 214, the end wall 222 of the transmission line shield 169, and the shield 169. At its tank end, the shield is in contact with the face plate 113. The inside of the bulge 131 is covered with the lining 147 that contacts the upper and lower skins of the grounded electrode 146 to complete the ground path.

A large flanged port 343, on the wall 107 of the synchro-cyclotron tank 91, is used as a point of entry for a breech loading probe 344. A cover-plate 345 that may be demountably secured to the flange in any convenient manner has a smaller rectangular section 346 welded in its mid-portion. A plate closure 347, removably mounted on the section 346, carries a short sleeve welded normal to its exterior surface; the sleeve is of such a diameter that it will just accommodate a long multi-walled tube 348. A chevron seal and gland within the sleeve are relied upon to retain the vacuum at this point.

A saddle 349 around the tube 348 near its outer end straps it to a small truck carried on four wheels. The wheels engage a pair of rails 351 beneath the tube. The truck is linked to an endless chain belt 352 that travels over a sprocket at either end of the rails. By linking a reversible motor 353 to the outermost sprocket 354 with a belt, the truck may be operated either toward or away from the tank 91. As this is done the tube 348 is respectively urged into or withdrawn from the tank. Thus with appropriate switch gear the probe tube may be caused to enter the tank any desired distance from the wall 107 to the center. In practice it has been found sufficient to limit the probe travel from a point 20.5 inches out on a radius to the edge of the pole face. While any of several positions for the probe would be feasible, in the instant structure the axis of the probe makes an angle of 15° with the Dee gap.

The plate 347 is also mounted on wheels (not shown) that engage the rails; and when it becomes necessary to service the probe the fasteners on the plate 347 may be removed and the entire probe 344 rolled away from the tank on the rails 351.

Cooling water is circulated between the walls of the tube 348 to help dissipate the heat that develops in the probe. For this purpose a hose 355 is coupled to the saddle 349 by means of a pipe fitting, and a passage in the saddle conducts water to the space between the walls of tube 348. The hose is ample in length to extend from a pipe source near the outer end of the rails to the region near the tank wall and therefore does not hamper

the travel of the probe. A trough 356 adjacent the rails is provided to receive the slack hose. A similar hose is provided to carry off the water discharged from the tube 348.

On the inner end of the tube 348 a target structure is mounted. Because of the experimental nature of the work done with a cyclotron the form of the target may be varied to suit the immediate problem. In general it includes a target vane, partially or wholly enclosed in an igloo or housing. The housing may incorporate a narrow slot to receive the beam of charged particles and allow them to impinge on the collector vane. Or the housing may be a thin vacuum tight metallic membrane inside of which the vane is mounted on a base. In this latter case the base and vane may be withdrawn through the tube without disturbing the vacuum in the tank, a new vane installed, and the base and new vane replaced in the igloo through the tube 348. Such a mechanism permits further measurements to be made at an old setting of the probe. In either case, the current collecting vane may be connected to some external current metering circuit as is indicated schematically in Fig. 1.

A great many useful investigations may be carried out with a cyclotron using a probe as above described within the vacuum environment in the tank. However for certain other types of research it is advantageous to remove the beam of charged particles from the tank.

If a cyclotron is to be flexible enough for both types of experiment some mechanism is required that can deflect the beam outwardly from the magnetic field. Accordingly provision is made for mounting a deflector on the cover plate 108 that constitutes the tank wall opposite the Dee. For this purpose a pair of bushing insulators 357 are mounted over apertures in the plate 108 with clamping rings 358 and fasteners of suitable type (not shown). A portion of a bushing extends through each aperture, and a metal conductor 359 is sealed in a hole along the axial center of each bushing. On these supports a deflector, of the general character shown schematically in Fig. 1, may be mounted and used to deflect the beam from the region between the magnet pole faces.

The center line of the Dee 129 does not pass through the line between the centers of the pole faces. Therefore, the vertical wall 361, which is a section of the curved wall of the Dee, is somewhat closer to the wall 106 of the tank 91 than is the vertical wall 362, another section of the Dee's curved wall, to the wall 107 of the tank 91. This arrangement of centers positions the Dee in such a way that it can receive the deflected orbit of the beam as it commences to straighten out. A window 363 in the wall 362 of the Dee provides an avenue of escape for the beam, and thus it comes to the window 364 in the tank wall 107. The window 364 has the same characteristics as the window 75 in Fig. 1 in that it can retain the vacuum that exists in the tank while permitting the high speed particles to pass on through without serious loss of energy and without appreciable scattering.

When a magnetic resonance accelerator of the character and magnitude embodied in the instant invention is being operated, it develops a radiation level in its immediate surroundings that makes it advisable to keep all personnel at a distance. With this in mind all controls for

the synchro-cyclotron are operable from a remote control room.

The magnet windings are energized by generators that supply 1500 amperes at 500 volts. At this operating power a substantially uniform field of about 15,000 gausses is maintained with the aid of the steps on the pole faces as shims.

For most operating conditions it has been found desirable to use a low voltage arc discharge type of ion source with a 100 mil D. C. filament enclosed by a graphite cone containing a small rectangular opening. The source 122, mounted at the inner extremity 124 of the arm 123, may be adjusted plus or minus three degrees in any direction in the horizontal plane by appropriate operation of the adjusting means 127 on the plate 125.

The single Dee 129 and the capacitor 176 are mounted at either end of a shielded line forming a resonant system whose frequency is variable between 12.6 and 9.0 megacycles. The system is excited by means of the grounded grid self-excited oscillator inductively coupled to a resonant circuit as described. A power input of 18 kilowatts to the plate circuit is sufficient to produce a Dee voltage of 15 kilovolts peak averaged over a modulation cycle.

It has been found desirable to enclose the Dee with grounded shields to reduce the volume available for glow discharges. Experience has also shown that a residual ionization is associated with low Dee voltages and tends to load the oscillator so that the Dee voltage cannot build up. To overcome this difficulty the usual procedure is to sweep the field free of ions by applying a few hundred volts of D. C. bias to the Dee system at the start of operations.

The frequency modulation of the resonant system depends directly upon the rotating mechanical vacuum capacitor from which frequencies up to 2000 C. P. S. are obtainable. Deuterons have been observed when the Dee voltage was as low as 8 kilovolts and the associated optimum capacitor speed was 120 R. P. M. This speed corresponds to a frequency of 48 C. P. S. Normal operation conditions are considered to include a Dee voltage of 15 kilovolts and a modulation frequency rate of 120 C. P. S. These are quite remarkable values when it is considered that original plans called for a Dee voltage of one million volts. With normal operating conditions prevailing the particles receive an average energy gain per revolution of only one half the maximum possible, and traverse a total number of turns of the order of 10^4 . The time of flight of particles from the ion source to a probe target at 80 inches radius has been measured at 890 microseconds.

For some types of study, particularly those in which a Wilson cloud chamber is used in conjunction with the cyclotron, it is advantageous to use a pulsed arc rather than a continuous one. During cloud chamber experiments both the arc voltage and the oscillator plate voltage may be triggered by the cloud chamber.

In operating the new and improved synchro-cyclotron under certain conditions and using deuterium in the source, the final energy of the particles has been found to be about 200 m. e. v. By the time the particles have reached their outer orbits they have revolved about 1300 times and traveled about 6 miles. Their speed at that time is nearly 90,000 miles per second or about 43% of the speed of light.

If after a thorough flushing of the gas lines 75

to the ion source, helium is introduced therein and the resultant alpha particles accelerated in the synchro-cyclotron, the final particle energies will be circa 400 m. e. v. These final particle energies that are obtainable with the synchro-cyclotron represent a threefold increase over the most optimistic predictions and are a vast improvement over anything achieved with heavy particles before.

10 In the synchro-cyclotrons hereinabove described, the energy of the accelerated ions is increased by decreasing the frequency of the oscillating electric field during the time that the ions are under the influence of the magnetic field of constant strength. By reference to Equation 3 it may be noted that the equilibrium angular velocity of charged particles can be increased in accordance with the present invention by increasing the ratio of the magnetic field strength to the frequency of oscillation of the electric field during the acceleration of the charged particles. In the preferred form of this invention, positively charged ions are accelerated to high energy by reducing the frequency of oscillation while keeping the magnetic field strength constant.

20 While I have described the salient features of this invention in detail with respect to one embodiment, it will, of course, be apparent that numerous modifications may be made within the spirit and scope of this invention; I do not, therefore, desire to limit the invention to the exact details shown except insofar as they may be defined in the following claims.

What is claimed is:

1. A rotating mechanical vacuum capacitor, for changing the resonant frequency of a cyclotron, including accelerating electrodes, comprising an evacuated envelope; fixed, toothed members mounted within said envelope and electrically connected to one of the accelerating electrodes of said cyclotron; rotatable, toothed members positioned between said fixed, toothed members; means for rotating said rotatable, toothed members including a supporting structure extending through a wall of said envelope, and an external source of power; insulating means mounted between said rotating means and said rotatable, toothed members; cooling means for said rotatable, toothed members and said insulator means provided within said rotating means; and capacitive coupling means between said insulator means and the other of said accelerating electrodes of said cyclotron.

2. A cyclotron having in combination a pair of electrodes, a source of alternating electric potential, and a rotary mechanical vacuum capacitor comprising an evacuated envelope, modulating means including fixed, toothed members mounted within said envelope and electrically connected to one of said electrodes, rotatable, toothed members positioned between said fixed toothed members, means for rotating said rotatable, toothed members including a supporting structure extending through a wall of said envelope, insulating means mounted between said rotating means and said rotatable toothed members; and coupling means comprising rotatable continuous members mounted on said insulating means, fixed continuous members positioned between said rotatable continuous members and electrically connected to the other of said electrodes.

3. In apparatus for accelerating charged particles, the combination comprising an evacuated tank, means for injecting charged particles centrally within said tank, means for establishing a

magnetic field of substantially constant value through said tank to force said particles to follow a curved path, a first electrode disposed within said tank and enclosing substantially half of the path of said particles, a second electrode surrounding said first electrode and having a diametral slot positioned normal to the path of said particles, a transmission line connected to said first and second electrodes and extended externally of said tank, a motor-driven variable capacitor connected at the extended end of said line, and an oscillator tube having its anode and cathode circuits coupled to said transmission line at spaced-apart positions.

4. In apparatus for accelerating charged particles, the combination comprising an evacuated tank, means for injecting charged particles centrally within said tank, means for establishing a magnetic field of substantially constant value through said tank to force said particles to follow a curved path, a first electrode disposed within said tank and enclosing substantially half of the path of said particles, a second electrode surrounding said first electrode and having a diametral slot positioned normal to the path of said particles, a rigid conductor connected at one end to said first electrode and extended at the other end externally of said tank, a plurality of spaced-apart parallel plates mounted on the extended end of said conductor, a rotor having a plurality of parallel plates disposed so that such plates interleave with the first-mentioned plates, driving

means attached to said rotor to provide rotation thereof, the plates of said rotor being coupled to said second electrode, and an oscillator tube having its anode and cathode circuits coupled to said conductor at spaced-apart positions.

EDWIN M. McMILLAN.
